CLAIM

The ornamental design for a child's rocking chair, as
shown and described.

DESCRIPTION

FIG. 1 is a perspective view of a child's rocking chair
showing my new design;
FIG. 2 is a front view of the rocking chair;
FIG. 3 is a side view of the rocking chair; and
FIG. 4 is a top view of the rocking chair.
The back of the rocking chair is plain and unornamented.
